UNITED STATES PATENT OFFICE.

BERNARD FRANCIS HORSTING, OF ST. LOUIS, MISSOURI.

HIDE-STRETCHER.

1,088,279.

Specification of Letters Patent.

Patented Feb. 24, 1914.

Application filed September 8, 1913. Serial No. 788,539.

To all whom it may concern:

Be it known that I, BERNARD FRANCIS HORSTING, a citizen of the United States, and a resident of St. Louis, Missouri, have invented certain new and useful Improvements in Hide-Stretchers, of which the following is a specification.

My invention relates to improvements in hide stretchers, and particularly to an apparatus for the stretching of hide butts, used in the manufacture of belting and the like, which butts have approximately parallel side edges, one end being approximately straight along its edge, which edge is at right angles to the side edges, while the opposing or neck end of the butt is irregular along its edge. In the apparatus of my invention I employ a series of horizontal and parallel suspended tracks, each provided with a rack slidably mounted upon its track by means of rollers, and a traveling carriage provided with means for receiving one rack at a time from its track. The rack is removed to the traveling mechanism in vertical position, is thrown to horizontal position, and there locked in alinement with a ram whereby the stretching of the hide upon the rack is effected. The traveling mechanism may thus be used in the operation of any desired number of stretching-racks, and dispenses with the necessity of equipping each rack with a stretching mechanism, as said racks have commonly been equipped in the prior art.

In the drawings—Figure 1 is a top plan view of a series of the suspended tracks. Fig. 2 is a side elevation of the rack-receiving and stretching mechanism, with a rack in place for stretching. Fig. 3 is a plan view of said traveling mechanism. Fig. 4 is a detail illustrating the horizontal adjustability of the ram. Fig. 5 is an elevation illustrating the means of locking the rack-receiving track of the traveling mechanism to the outer end of one of the fixed tracks. Fig. 6 is a top plan view of a portion of the same. Fig. 7 is a perspective view of the extremity of the stretching rod. Fig. 8 is a similar view of the end of the stretching rod secured to the lower jaw of a rack. Fig. 9 is an enlarged detail view of the spring connection between the ram and the cross-head of the stretching carriage. Fig. 10 is an enlarged detail view of the wedge locking the lower jaw of a rack to the tubular bar.

In the drawings the fixed tracks 11 are

mounted horizontally upon the supporting beam 12 which is secured to the wall of a building by brackets 13—13. Each of the tracks 11 is adapted to receive a rack 14, which is suspended upon the wheels or rollers 15, which are attached by straps 16 to the block 17. Tubular bars 18—18 are fixedly mounted parallel to each other in the block 17, and upon their lower extremities the block 19 is slidably mounted by means of collars 20.

The upper face of the block 19 is ratcheted as indicated by the numeral 21, and a transverse clamp 22 is removably secured to the face of the block 19 by means of bolts 23, this clamp being adapted to secure the straight end of the hide butt to be stretched. The irregular end of the hide butt is held upon the ratcheted face 24 of the block 17 by means of the independently adjustable grippers 25, secured in place by bolts 26, which bolts 26 pass through the slots 27 in the block 17. The rack so constructed is normally, and when not in place upon the traveling mechanism, suspended vertically from one of the tracks 11.

The traveling carriage illustrated in Fig. 2 comprises a frame 27 supported upon wheels 28 which run upon the track 29. Upon the frame 27 are mounted uprights 30 and 31. At the top of the uprights 30 the arms 32—32 are pivotally mounted and provided at their outer ends with the track member 33 and at their inner ends with the counter balancing weights 34—34. The track-member 33 is provided with locking bars 35—35, which are slidably mounted upon the opposite faces of the track-member 33 by means of bolts 36—36 which pass through the slotted opening 37 in the track-member 33 (see Fig. 5). The hand lever 38 is connected to the locking bars 35—35 by the rod 39, so that when the arms 32—32 are swung into vertical position, and the carriage frame 27 is moved to such a point as to bring the tracks 11 and 33 into alinement, the action of the lever 38 is invoked to thrust the locking bars 35—35 into position to lock the tracks 11 and 33 in alinement as illustrated in Fig. 6. The rack 14 is then pulled outwardly into position upon the track-member 33, when the locking bars 35—35 are released, and the rack is brought into horizontal position as illustrated in Fig. 2.

The chain 40, attached at the extremities

to the upright 31 and to one of the arms 32 serves to limit the upward movement of the arms 32; the spring-pawl 41 serves to engage with the projection 42 on the counter balance bar 43, to lock it in its lowest position.

The frame 27 carries the platform 44, from which projects the perforated arm 45, through the perforation in which a bar 46 is inserted, with its lower end upon the floor sustaining the track 29, so that the bar 46 may be used as a lever to propel the frame 27.

The frame 27 carries the upright 47-48 upon which the ram or piston 49 is seated in the frame 50 (said frame 50 having cross bars 51-52), the frame 50 having projecting lugs 53 which engage with the interiors of the tubular bars 18-18. The frame 50 is rendered adjustable horizontally by means of the hand wheel 54, mounted in the bracket 55, the bracket 55 being secured to the upright 47. The hand wheel 54 operates the shaft 56 which is provided at its inner end with the gear-wheel 57, engaging with the rack 58 with which the bottom of the ram or piston 49 is provided. The carriage 50 is supported on wheels 59, operating in the track 60.

The stretching rods 61-61 are provided at their outer ends with upwardly projecting lugs 62 which fit into openings in the lower face of the block 19, and are there locked by means of clamps 63. A cross-head 64 is journaled at its ends to receive the stretching-rods 61-61, each of which rods 61 is provided with nuts 65, which said rods are screw threaded to receive. The thrust rod 66 is mounted in a piston, not shown, in the ram or cylinder 49. Said ram or cylinder 49 is provided with the inlet pipe 67, into which fluid is forced by the hand pump 68 to drive the piston and rod 66, to stretch the hide mounted in the rack 14. When the work is sufficiently stretched, the collars 20 are locked in place upon the tubular bars 18 by means of wedges 69, whose inner faces bear against the ratcheted faces 70 with which the bars 18 are provided. The hide being sufficiently stretched, the stretching carriage 50 is adjusted by means of the hand-wheel 54 to release the rack 14 by withdrawing the pro-

jections 53 from the openings in the tubular bars 18; whereupon the rack is brought to 55 vertical position, the track member 33 is brought into alinement with one of the tracks 11, and locked in said position as hereinabove described, whereupon the rack 14 is slid onto the track 11, and there left, 60 in vertical position until the work is sufficiently stretched.

Having thus described my invention what I claim as new and desire to have secured to me by the grant of Letters Patent, is— 65

1. The improvement in hide stretchers comprising a series of horizontal and parallel suspended tracks, racks removably mounted on said tracks, and a traveling stretcher adapted to successively register 70 with said tracks and to successively receive said racks.

2. In a hide stretcher, in combination, a traveling stretcher provided with a track-bar; a series of suspended tracks; means for 75 bringing said track-bar into successive engagement with said tracks, and extensible racks carried by said tracks, and adapted to be transferred successively from said tracks to said stretcher. 80

3. In a hide stretcher, a series of extensible racks, a plurality of independently adjustable grippers mounted in series at one end of each of said racks, a clamp mounted on the opposing end of each of said racks, 85 and a single stretching mechanism whereby said racks are successively operated to stretch hides held on said racks by said grippers.

4. In a hide stretcher, a traveling carriage, a tilting frame carried thereby, a ram mounted on said carriage, a rack having a fixed jaw and a movable jaw, adapted to be received and held by said frame in vertical position; means for holding said rack in 95 horizontal position, and means for connecting the movable jaw of said rack with said ram. 90

In testimony whereof, I have signed my name to this specification, in presence of 100 two subscribing witnesses.

BERNARD FRANCIS HORSTING.
